ELECTRIC TRAFFIC SIGNAL

James Henry Brady, Louisville, Ky.

Application October 14, 1937, Serial No. 169,013

12 Claims. (Cl. 177—328)

The invention relates to electric traffic signals, having for an object to provide signal lights of contrasting colors in horizontal ribbon form, using the common neon lights for the red signals and the proper gas used instead of neon for the green signals. Another object is to provide such ribbon-form lights at right angles to each other and a holder for said lights having arms at right angles to each other and open at opposite sides to permit the lights to show through so that each light will face in opposite directions. Another object is to provide the holder with a control box located at the intersection of the arms thereof and having therein located the means for electrically illuminating and extinguishing the lights in timed relation. Another object is to provide said arms of the holder with shields at the free ends of the arms to prevent confusion of signals. Another object is to provide the signal lights of contrasting colors in two sets facing traffic in different directions, each set comprising a plurality of lights of each of the contrasting colors, the contrasting color lights of the two sets being simultaneously illuminated and thereafter extinguished one by one at equal time intervals until all are extinguished so that the stop and go periods will be divided into parts to clearly indicate what portions of the periods remain for traffic to use, after which the signal lights of the opposite color of each set are simultaneously illuminated and thereafter extinguished one by one at equal time intervals until all are extinguished to complete one of repeated cycles. Another object is to provide such a traffic signal of economical construction and simple operation. Another object is to provide means to shield traffic from any bright light located beyond the signal lights shining through the signal lights. Other objects and advantages will hereinafter appear.

40 The invention consists in the novel construction and combinations of parts as hereinafter set forth in the claims.

In the accompanying drawings:

Figure 1 is a front perspective view of the signal lights and the holder therefor.

Figure 2 is a horizontal cross sectional view of the same.

Figure 3 is a detail plan view of one of the light tubes.

50 Figure 4 is a detail side view of the control timer.

Figure 5 is a detail end view of the same, with the shaft in section.

55 Figure 6 is a diagrammatic view, showing the invention as in use for intersecting streets.

Figure 7 is a diagrammatic view of the wiring, the transformers, the light tubes, the cams, etc.

In these drawings, the numeral 1 designates the vertical support or holder for the horizontally extended signal lights to be described, said holder 5 having two horizontally extended arms 2, at right angles to each other and being of L-shape.

Each of the arms 2, 2, is hollow and is provided with a vertical transverse partition 5, having perforations 6, engaged by the arms of transparent 10 U-shaped tubes 7, to support said tubes in horizontal position, said tubes containing each a gas showing a distinctive color when an electric current is passed therethrough, such as neon for the red signals and the proper gas used instead of 15 neon for the green signals. These tubes are arranged in vertical series within said holder, one set of said tubes being located within each arm 2 of the holder, namely a set of a plurality of live green illuminated tubes or lights and a plurality 20 of dead red extinguished tubes or lights facing traffic going in opposite directions on one street, and a set of a plurality of dead extinguished green tubes or lights and a plurality of live illuminated red tubes or lights facing traffic going 25 in opposite directions on an intersecting street, the control box to be described containing electrically controlled means for illuminating said live green tubes and said live red tubes simultaneously, for thereafter extinguishing the lights 30 of each color one by one at equal time intervals until all are extinguished, for illuminating said dead green tubes and said dead red tubes simultaneously and for thereafter extinguishing the tubes of each color one by one at equal time 35 intervals until all are extinguished to complete a cycle. The U-shaped tubes 7 are adapted to be readily engaged with the perforations 6 of the partitions 5, being inserted through the outer open ends of each of the arms 2, said ends being 40 afterwards closed by a suitable closure 8, which may be readily removed and replaced for ready access to said tubes for removal and replacement thereof. The U-shaped tubes 7 are arranged each with both arms or branches thereof in the same 45 horizontal plane, and when lighted up shine through both sides of each of the arms 2 of the support or holder, which sides are open and glass inclosed at 9.

The horizontally extended signal lights 1 are 50 spaced outwardly of the horizontally extended arms 2 of the holder 1 sufficiently to show the entire signal lights from one end thereof to the other to all approaching traffic up to and including the stopping points of said traffic at the 55

intersection of the streets, and to provide a vacant space constituting a control box 3, located at the intersection of said arms 2, and containing the means for electrically illuminating and extinguishing the signal lights in timed relation to be described.

The end closures 8, for the outer ends of the hollow arms 2 of the holder or support, in conjunction with lateral extensions 8a, of said closures, afford shields extending around the end portions of the signal lights to prevent confusion of signals, or so that traffic approaching the signal lights along one street will not see the signal lights controlling traffic on the intersecting street.

Means are provided to shield traffic from any bright light located beyond the signal lights shining through the signal lights, comprising a vertical opaque partition 10, located in the intervals 20 between the arms or branches of each set of the signal tubes 7, said partition being notched at 10a, to receive the central portions of the bends of the U-shaped tubes 7 to aid in supporting said tubes in horizontal position within the holder or support.

The electrical illumination and extinguishing of the signal lights in repeated cycles as aforesaid is accomplished by means described as follows:

Each of the U-shaped tubes 7 has the free ends 30 of the arms or branches thereof provided with metallic ferrules 11, which when the tubes are placed in position in the support or holder make electrical contact with wires 12 of a small transformer 13, which is adapted to step up the electric current from 110 volts to 2000 volts. Each transformer 13 lights up two tubes 7 only, namely one green tube located in one of the arms 2 of said support and one red tube located in the other arm 2 of said support, so that when the 40 green tubes are alone illuminated for one street, the red tubes will be illuminated alone for the intersecting street.

There are eight of these small transformers 13 for the complete signal device operating eight 45 pairs of the U-shaped tubes 7, which number sixteen U-shaped tubes in all.

The 110 volt electric current wiring is connected with a control device or timer, consisting of a motor 14, such for instance as is used for the 50 common electrical clock and driving a shaft 15, whereon are carried a plurality of cams 16, each having a circumferential notched portion 17, these notched portions being of different contour, spring fingers 18 being normally held outwardly 55 by the unnotched circumferential portions of the cams and when engaging the notched portions of the cams during the rotation of the latter moving inwardly through inherent spring to cause the free ends of said fingers to make electrical 60 contact at 19 with the aforesaid transformers to conduct the 110 volt supply current thereto.

Due to the arrangement or setting of the cams 16 to dispose the notched portions 17 thereof in proper order and to the different contour of said 65 notched portions, the U-shaped tubes 7 constituting the signal lights will be illuminated and extinguished in repeated cycles as stated.

The shaft 15 and the cams thereof rotate for example once per minute, the notched portion 17 in each cam making the electrical contact for the length of time desired for each pair of light tubes. The first cam 16 makes the contact for the topmost green tube in one arm of the holder and the topmost red tube in the other arm thereof, these 75 tubes staying lighted for only one-eighth of a

minute (seven and one-half seconds). The second cam 16 makes the electrical contact at the same time that the first cam does, but holds the contact for one-fourth of a minute (fifteen seconds). The third cam 16 makes the contact at 5 the same instant that the first and second cams do, but holds the contact twenty two and one-half seconds. The fourth cam 16 makes the contact at the same instant that the first, second and third cams do, and holds its contact for thirty 10 seconds.

Thus all four light tubes of the one color in one arm of the holder are illuminated simultaneously with the four light tubes of the contrasting color in the other arm of the holder, after which the 15 contact is broken by the first cam 16 and the uppermost green tube in one arm of the holder and the uppermost red tube in the other arm thereof are simultaneously extinguished, leaving three green tubes and three red tubes still illuminated. Then the second cam 16 breaks its contact and the next pair of tubes of contrasting colors are simultaneously extinguished. Then the third cam 16 breaks its contact and the next pair of tubes of contrasting colors are simultaneously 20 extinguished. Finally the fourth cam 16 breaks its contact and the fourth pair of tubes of contrasting colors are simultaneously extinguished. By this time, the shaft 15 and the cams 16 have made one half of a rotation and have 30 affected the four green tubes in one arm of the holder and the four red tubes in the other arm thereof. At this time, said cams are adapted to permit the four spring fingers 18 on the other side of the timer to spring into place, 35 which makes the contact to illuminate simultaneously the other eight pairs of tubes previously unaffected, etc. In other words, all four of the cams 16 make the electrical contact at the same instant, but these four contacts are broken one 40 at a time, etc.

I claim:

1. In an electric traffic signal unit, two horizontally extended signal lights of contrasting colors facing traffic going in opposite directions 45 on one street, two horizontally extended signal lights of contrasting colors at right angles to the first named lights facing traffic going in opposite directions on an intersecting street, and an L-form holder for said signal lights having two 50 horizontally extended arms at right angles to each other, each arm being open at opposite sides to permit the signal lights to show through, said signal lights being spaced outwardly of the arms of said holder sufficiently to show the entire signal lights to all approaching traffic up to and including the stopping points of said traffic at the street intersection.

2. In an electric traffic signal unit, two horizontally extended signal lights of contrasting colors facing traffic going in opposite directions on one street, two horizontally extended signal lights of contrasting colors at right angles to the first named lights facing traffic going in opposite directions on an intersecting street, and an L-form holder for said signal lights having two 65 horizontally extended arms at right angles to each other, each arm being open at opposite sides to permit the signal lights to show through, said signal lights being spaced outwardly of the arms of said holder sufficiently to show the entire signal lights to all approaching traffic at the street intersection and to provide a vacant space constituting a control box at the intersection of the holder arms and means for electrically illuminating and 70 75

extinguishing said lights in timed relation located in said control box.

first named lights facing traffic going in opposite directions on an intersecting street, an L-form holder for said signal lights having two horizontally extended arms at right angles to each other, each arm being open at opposite sides to permit the lights to show through, said arms having shields extending around the end portions of said lights to prevent confusion of signals, said signal lights being spaced outwardly of the arms of said holder sufficiently to show the entire signal lights to all approaching traffic up to and including the stopping points of said traffic at the street intersection.

20 4. In an electric traffic signal unit, two horizontally extended signal lights of contrasting colors facing traffic going in opposite directions on one street, two horizontally extended signal lights of contrasting colors at right angles to the first named lights facing traffic going in opposite directions on an intersecting street, each of said signal lights comprising a transparent tube containing a gas showing a distinctive color when an
25 30 electric current is passed therethrough, said unit having a single holder and a single location.

5. In an electric traffic signal unit, two horizontally extended signal lights of contrasting colors facing traffic going in opposite directions on one street, two horizontally extended signal lights of contrasting colors at right angles to the first named lights facing traffic going in opposite directions on an intersecting street, each of said signal lights comprising a transparent tube containing a gas showing a distinctive color when an electric current is passed therethrough, and an L-form holder for said signal lights having two horizontally extended arms at right angles to each other, each arm being open at opposite sides to permit the lights to shine through, said signal lights being spaced outwardly of the arms of said holder sufficiently to show the entire signal lights to all approaching traffic up to and including the stopping points of said traffic at the street intersection and to provide a vacant space constituting a control box at the arms intersection, and means for electrically illuminating and extinguishing said lights in timed relation located in said control box.

55 6. In an electric traffic signal unit, two horizontally extended lights of contrasting colors facing traffic going in opposite directions on one street, two horizontally extended signal lights of contrasting colors at right angles to the first
60 named lights facing traffic going in opposite directions on an intersecting street, each of said signal lights comprising a transparent tube containing a gas showing a distinctive color when an electric current is passed therethrough, and an
65 L-form holder for said signal lights having two horizontally extended arms at right angles to each other and wherein the two sets of lights are located, said holder being open at opposite sides to permit the lights to shine through, said arms
70 having shields extending around the end portions of said lights to prevent confusion of signals, said signal lights being spaced outwardly of the arms of said holder sufficiently to show the entire signal lights to all approaching traffic up to and includ-
75 ing the stopping points of said traffic at the street

intersection and to provide a vacant space constituting a control box at the arms intersection.

7. In an electric traffic signal unit, two horizontally extended signal lights of contrasting colors facing traffic going in opposite directions on one street, two horizontally extended signal lights of contrasting colors at right angles to the first named lights facing traffic going in opposite directions on an intersecting street, each of said lights comprising a U-shaped transparent tube the branches of which are in the same horizontal plane and containing a gas showing a distinctive color when an electric current is passed therethrough, said unit having a single holder and a single location. 15 10 15

8. In an electric traffic signal unit, two horizontally extended signal lights of contrasting colors facing traffic going in opposite directions on one street, two horizontally extended signal lights of contrasting colors at right angles to the first named lights facing traffic going in opposite directions on an intersecting street, each of said lights comprising a U-shaped transparent tube the branches of which are in the same horizontal plane and containing a gas showing a distinctive color when an electric current is passed therethrough, and vertical opaque screen means located between the branches of said tubes for shielding traffic from any bright light located beyond the signal lights shining through the signal lights. 20 25 30

9. In an electric traffic signal unit, a set of a plurality of live green lights and a plurality of dead red lights facing traffic in one direction, a set of a plurality of live red lights and a plurality of dead green lights facing traffic in another direction, and electrically controlled means for illuminating said live green and live red lights simultaneously, for thereafter extinguishing the lights of each color one by one at equal time intervals until all are extinguished, for illuminating said dead green lights and dead red lights simultaneously and for thereafter extinguishing the lights of each color one by one at equal time intervals until all are extinguished to complete a cycle, said unit having a single holder and a single location. 35 40 45

10. In an electric traffic signal unit, a set of a plurality of live green lights and a plurality of dead red lights facing traffic going in opposite directions on one street, a set of a plurality of live red lights and a plurality of dead green lights facing traffic going in opposite directions on an intersecting street, and electrically controlled means for illuminating the live green lights and live red lights simultaneously, for thereafter extinguishing the lights of each color one by one at equal time intervals until all are extinguished, for illuminating said dead green lights and dead red lights simultaneously and for thereafter extinguishing the lights of each color one by one at equal time intervals until all are extinguished to complete a cycle, said unit having a single holder and a single location. 50 55 60

11. In an electric traffic signal unit, a set of a plurality of live green lights and a plurality of dead red lights facing traffic going in opposite directions on one street, a set of a plurality of live red lights and a plurality of dead green lights facing traffic going in opposite directions on an intersecting street, and electrically controlled means for illuminating the live green lights and live red lights simultaneously, for thereafter extinguishing the lights of each color one by one at equal time intervals until all are extinguished, for illuminating said dead green lights and dead red lights simultaneously, and for thereafter extinguishing the lights of each color one by one at equal time intervals until all are extinguished, 65 70 75

- red lights simultaneously, for thereafter extinguishing the lights of each color one by one at equal time intervals until all are extinguished to complete a cycle, each of said lights being horizontally extended, and an L-form holder for said lights having horizontally extended arms open at opposite sides to permit the lights to show through, said signal lights being spaced outwardly of the arms of said holder sufficiently to show the entire 5 signal lights to all approaching traffic up to and including the stopping points of said traffic at the street intersection and to provide a vacant space constituting a box for said electrically controlled means located at the arms intersection of said 10 holder.
12. In an electric traffic signal unit, a set of a plurality of live green lights and a plurality of dead red lights facing traffic going in opposite directions on one street, a set of a plurality of 15 live red lights and a plurality of dead green lights facing traffic going in opposite directions on an intersecting street, electrically controlled means for illuminating said live green lights and said live red lights simultaneously, for thereafter extinguishing the lights of each color one by one at equal time intervals until all are extinguished, for illuminating said dead green lights and dead 20 red lights simultaneously and for thereafter extinguishing the lights of each color one by one at equal time intervals until all are extinguished to complete a cycle, each of said lights being horizontally extended, and an L-form holder for the two sets of tubes open at opposite sides to permit the lights to show through, said holder having two horizontally extended arms at right angles to each other and each arm containing one of said sets of tubes, and an opaque vertical partition located in the intervals between the branches of all of the tubes of each set to thereby shield traffic from any bright 1 light located beyond the signal lights shining through the signal lights, said holder arms having shields extending around the end portions of said tubes to prevent confusion of signals, said signal lights being spaced outwardly of the arms of said 25 holder sufficiently to show the entire signal lights to all approaching traffic up to and including the stopping points of said traffic at the street intersection and to provide a vacant space constituting a box for said electrically controlled means located at the arms intersection of said holder.

JAMES HENRY BRADY.
